Primary Examiner — Catherine R Oliver-Garcia

(74) Attorney, Agent, or Firm — Oliff PLC

(57) **CLAIM**

The ornamental design for a reel seat for fishing rod as shown and described.

DESCRIPTION

FIG. 1 is a front, left-side, bottom perspective view of a reel seat for fishing rod, showing the new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof;

FIG. 7 is a bottom plan view thereof;

FIG. 8 is a front, right-side, top perspective view thereof;

FIG. 9 is a cross-sectional view taken along line 9-9 in FIG. 2; and,

FIG. 10 is a cross-sectional view taken along line 10-10 in FIG. 4.

1 Claim, 6 Drawing Sheets
